(57) **CLAIM**

The ornamental design for an automatic draining round pool cover, as shown and described.

DESCRIPTION

FIG. 1 is a perspective view of an automatic draining round pool cover showing my new design;

FIG. 2 is another perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top plan view thereof; and

FIG. 8 is a bottom plan view thereof;

FIG. 9 is a partial enlarged view of portion 9 in FIG. 1;

FIG. 10 is a partial enlarged view of portion 10 in FIG. 2; and,

FIG. 11 is a partial enlarged view of portion 11 in FIG. 2. The broken lines depict portions of the automatic draining round pool cover and form no part of the claimed design. The dot-dash lines depict the boundaries of the enlarged views and also form no part of the claimed design.

1 Claim, 11 Drawing Sheets
